[57] CLAIM

The ornamental design for a shoe cover, as shown and described.

DESCRIPTION

FIG. 1 is a top plan view of the shoe cover showing my new design;

FIG. 2 is a front elevational view thereof, and the rear elevational view being an mirror image;

FIG. 3 is a bottom plan view thereof;

FIG. 4 is a left side elevational view thereof;

FIG. 5 is a right side elevational view thereof; and,
FIG. 6 is a perspective view taken from the top, front and left side of the shoe cover placed on a shoe.

The broken line showing of a high heel in FIG. 6 is for illustrative purposes only and forms no part of the claimed design.

FIG. 1

FIG. 2

FIG. 3

FIG.4

FIG.5

FIG. 6
